UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed October 16, 1930. Serial No. 489,019.

This invention relates to mining machines, and more particularly to improvements in the guiding means for the flexible feeding means of a coal mining machine of the flexibly fed type.

An object of this invention is to provide an improved guiding means for the flexible feeding means of a coal mining machine. Another object is to provide an improved adjustable mounting structure for the guiding means. A further object is to provide an improved arrangement of the guiding means on the machine whereby the flexible feeding elements may be guided in an improved manner relative to the machine feeding members. Still another object is to provide improved guiding means whereby a flexible feeding element may be extended in a plurality of directions from the feeding member on the machine. Another object is to provide an improved pivotal mounting for a guide sheave. These and other objects will, however, hereinafter more fully appear.

In the accompanying drawing there is shown for purposes of illustration one form which the invention may assume in practice.

In this drawing,—

Fig. 1 is a plan view of a coal mining machine equipped with the illustrative embodiment of the improved guiding means.

Fig. 2 is a fragmentary side elevational view of the machine shown in Fig. 1.

Fig. 3 is an end elevational view of the machine shown in Fig. 1 with the swingable side guides in a different position, parts of the improved guiding means being shown in section to illustrate structural details.

Fig. 4 is a vertical sectional view taken substantially on line 4—4 of Fig. 3.

Fig. 5 is a vertical sectional view taken on line 5—5 of Fig. 3.

Fig. 6 is a vertical sectional view taken on line 6—6 of Fig. 3 with the outer guide support in its upper position.

Fig. 7 is a detail sectional view taken on line 7—7 of Fig. 4.

In this illustrative embodiment of the invention the improved guiding means are shown mounted on a mining machine of the flexibly fed, room and pillar type although

it is evident that the same may be embodied in machines of various other types. The mining machine generally designated 1, which may be of the same general type as that disclosed in my copending application Ser. No. 367,895, filed June 3, 1929, consists of a generally rectangular machine frame 2 slidable on its bottom 3 over the mine floor. Projecting forwardly lengthwise of the machine frame is a usual horizontal plane cutter bar 4 carrying on its margin a cutter bit carrying cutter chain 5. In the present construction, mounted on the opposite sides of the rear end of the machine frame for rotation in opposite directions about aligned transverse axes are feed operating and controlling members 6 and 7 herein in the form of cable winding or haulage drums with which respectively cooperate flexible feeding and controlling elements 8 and 9 herein the form of cables or ropes.

Now referring to the improved guiding means for the feeding and controlling cables 8 and 9, it will be noted that mounted on the opposite sides of the forward end of the machine frame are guide sheaves or rolls 10 and 11 with which the feeding and controlling cables 8 and 9 are adapted to respectively cooperate. Also arranged transversely of the machine frame at the rear end of the machine is a horizontal shaft or cylindrical bar 12 secured as by welding or otherwise to a projecting ledge 13 integral with the frame and projecting through openings 14 formed in vertical projections 15. The projections 15 project rearwardly from the opposite sides of the machine frame and in the present instance are formed integral with the latter, and the shaft or bar 12 is held rigid with respect to these projections as by welding. This shaft or bar has projecting ends forming supports for certain of the guiding elements as hereinafter described. Pivotedly mounted at 16 on the ledge 13 intermediate the sides of the machine is a horizontally swingable arm 17 carrying a guide sheave or roll 18. Spaced stop pins 19 and 20 secured to the ledge, limit swinging movement of the arm 17 about its pivot in opposite directions, the arm being swingable to position 100.

the guide sheave at opposite sides of the longitudinal vertical center of the machine. A support 21 having an opening 22 through which one end of the shaft or bar 12 projects is mounted on the shaft and has formed integral therewith a stub shaft 23 inclined slightly with respect to the vertical. Journaled on the shaft 23 is a guide sheave or roll 24. To prevent movement of the support 21 about the axis of the shaft 12 there is provided on the support a projecting lug 25 which engages a plane abutment surface 26 formed on the adjacent projection 15. Arranged adjacent the support 21 and pivotally mounted on the shaft 12 is a swingable support or swing arm 27 having an integral stub shaft 28 on which a guide sheave or roll 29 is journaled. This support or swing arm is retained in position on the shaft by means of a cup-shaped retaining element 30 having a key portion 31 fitting a key way 32 traversing the end of the shaft. This key and keyway prevent rotative movement of the retaining element with respect to the shaft. The retaining element is held in position on the end of the shaft by means of a screw 33 passing through an aperture in the retaining element and threadedly secured to the shaft. Formed centrally within the stub shaft 28 is a bore 34 in which is mounted a spring-pressed plunger 35 having a suitable handle 36. This plunger is engageable with either of two apertures 37, 38 formed in the retaining element 30 to lock the swing arm or sheave support 27 in either of two positions. In assembling this improved guide structure the sheave support 21 is first slid in position on the projecting end of the shaft 12 with the abutment 25 engaging the abutment surface 26 on the projection 15. The swivel support or swing arm 27 is then slid in position on the sheave in abutting engagement with the support 21 and these parts are held in position by means of the retaining element 30 secured to the shaft by the screw 33. When the plunger 35 is released from the retaining element 30 the sheave support or swing arm 27 is free to swing about the shaft to position the guide sheave 29 in planes adjacent the bottom or top of the feed drum 6. To limit the upward swinging movement of the swing arm there is provided a projecting lug 39 formed on the support 27 and engageable with a lug 40 formed on the support 21. Downward swinging movement of the support 27 is limited by an abutment 41 formed on the machine frame. The swing arm is locked in position against either abutment by the locking plunger 35. Arranged at the opposite side of the machine is a support 43, similar to the support 21, and carrying a similar guide sheave 44, while pivotally mounted on the projecting end of the shaft 12 is a swingable support or swing arm 45, similar to the swing arm 27, carrying a simi-

lar guide sheave 46. As the structure of the guiding arrangement at this side of the machine is identical to the guiding structure above described, further detailed description of the same is thought unnecessary other than to state that the swing arm 45 may be swung into either of two positions to locate the guide sheave 46 in planes adjacent the bottom or top of the control drum 7.

In the use of the improved guiding means during the cutting operation of the machine with the parts as shown in Fig. 1, the feed cable 8 wound on the drum 6 is extended from the bottom of the drum forwardly along the side of the machine around the guide sheave 10 and laterally from the machine to a suitable anchor. The controlling cable 9 wound on the control drum 7 is extended from the bottom of the drum rearwardly around the guide sheave 46, the swing arm 85 or support 45 at that time being in its lowermost position and laterally from the machine to a suitable anchor located at the receding side of the machine. As the feed drum is rotated by power the cable 8 is wound in, thereby drawing the machine bodily over the mine floor to feed the cutter bar 4 transversely across the coal face. The control cable 9 and control drum 7 guide the machine during its transverse feeding movement and control the angle of the cutter bar with respect to the coal face. When it is desired to haul the machine about the mine, for instance to move the machine from the coal face to its transport truck, the feed cable 8 may be detached from the guide sheave 10 and extended from the top of the feed drum 6 around the guide sheave 29 which, at this time, is swung and locked in its uppermost position as shown in Figs. 1 and 2, the feed cable 8 passing around the guide sheave 29 rearwardly of the machine to a suitable anchor located adjacent the machine transport truck. Upon rotation of the drum 6 by power the cable 8 is wound in, drawing the machine bodily over the mine bottom. When the machine is cutting in a direction opposite from that shown in Fig. 1, that is from left to right, the direction of rotation of the drums 6 and 8 is reversed and the cables rewound on their respective drums. At that time the guide sheave 29 is swung downwardly from the position shown in Figs. 1 and 2 to the positions shown in Figs. 3 and 4, while the guide sheave 46 is swung upwardly from the position shown in Figs. 1 and 2 to the position shown in Fig. 3. The cable 9 is then extended from the bottom of the drum 7 forwardly along the side of the machine around the guide sheave 11 and laterally from the machine to an anchor located at the rear of the machine. Upon rotation of the drums 6 and 7 the machine is then drawn over the mine floor to effect the transverse feeding movement of the cutter 125 130 135 140 145 150 155 160 165 170 175 180 185 190 195 200 10135 10140 10145

bar 4 across the face of the coal in a left to right direction. When the parts are so arranged and it is desired to feed the machine bodily over the mine floor from the coal face to its transport truck or to change the position of the machine in the room, the cable 9 is extended from the top of the drum 7 around the guide sheave 46 and rearwardly from the machine to a suitable anchor, and upon rotation of the drum 7 the machine is drawn bodily over the mine floor. Under certain conditions it is desirable for the drums 6 and 7 to rotate in the same direction with the cable extending from the bottom of the drum 6 around the guide sheave 10 while the cable 9 extends from the top of the drum 7 around the guide sheave 46 and rearwardly from the machine to its anchor. At that time both of the guide sheaves 29 and 46 are swung and locked in their uppermost position. During loading of the machine on to its transport truck, or if for any reason it is desired to move the machine in the direction of its length in a straight path, the cable 8 may be extended from the top of the drum 6 around the guide sheave 24, then transversely of the machine and around the guide sheave 18 and then rearwardly of the machine to a suitable anchor, the sheave 18 at that time being located in the full line position shown in Fig. 1. When the cable 9 is rewound on the drum 7 it may be extended from the top of the drum 7 around the guide sheave 44 across the machine and around the guide sheave 18, the latter being at that time in a dotted line position shown in Fig. 1.

As a result of this invention it will be noted that an improved guiding means is provided for the flexible feeding means of a coal mining machine, whereby the flexible feeding elements may be extended from the feeding members on the machine in various directions in an improved manner. It will further be noted that by the provision of swingable mountings for certain of the guide sheaves it is possible to guide the feed cables when extended from either the bottoms or tops of the drums. It will still further be evident that by the provision of the loading sheave at the center of the machine it is possible to extend the feed cable from either drum and rearwardly from the machine so that the pull of the cable will be substantially at the longitudinal vertical center of the machine, and as a result enabling the machine to be fed in a substantially straight path in the direction of its length. These and other uses and advantages of the improved guiding means will be clearly apparent to those skilled in the art. While there is in this application specifically described one form which the invention may assume in practice, it will be understood that this form of the same is shown for purposes of illustration and that the invention may be modified and embodied in various

other forms without departing from its spirit or the scope of the appended claims.

What I claim as new and desire to secure by Letters Patent is:

1. In a mining machine having a forwardly projecting cutter bar, the combination with a feed member and a cooperating flexible feeding element, of guiding means for said flexible element including a swing arm pivotally mounted at the rear of said feed member at the rear end of the machine remote from said cutter bar and carrying a guide sheave, said arm being swingable to locate said sheave in different elevated positions whereby it may be engaged by said flexible element when the latter is extended in a plurality of directions from said feed member. 70
2. In a mining machine, the combination with a feed member and a cooperating flexible feeding element, of guiding means for said flexible element including a swing arm disposed adjacent said feed member and carrying a guide sheave rotatable about an axis perpendicular to the arm pivot axis, said arm being swingable to locate said sheave in different elevated positions whereby it may be engaged by said flexible element when the latter is extended in a plurality of directions from said feed member. 85
3. In a mining machine, the combination with a feed member and a cooperating flexible feeding element, of guiding means for said flexible element including a swing arm carrying a guide sheave rotatable about an axis at right angles to the arm pivot axis, said arm being swingable vertically to locate said sheave into positions whereby it may be engaged by said guide laterally said flexible element when the latter is extended directly from either the top or bottom of said feed member. 95
4. In a mining machine, the combination with a feed member and a cooperating flexible feeding element, of guiding means for said flexible element including a swing arm disposed adjacent said feed member and swingable about an axis parallel with the axis of said feed member at the rear of the latter at the rear end of the machine and carrying a guide sheave, said arm being swingable to locate said sheave in different elevated positions whereby it may be engaged by said flexible element when the latter is extended in a plurality of directions from said feed member. 105
5. In a mining machine, the combination with a pair of feed members thereon and cooperating flexible feeding elements, of guiding means for said flexible elements including an arm pivoted at the longitudinal vertical center of the machine and carrying a guide sheave and swingable to position said sheave at either side of the longitudinal vertical center of the machine whereby either flexible 115
- 120
- 125
- 130

element may be extended from said guide sheave along the central vertical plane of the machine.

6. In a mining machine, the combination with a plurality of feed members and flexible feeding elements cooperating respectively therewith, of guiding means for said flexible elements including a guide sheave adjustable into a plurality of positions on the machine, said sheave when in one position adapted to be engaged by one flexible element and when in another position by said other flexible element.

7. In a mining machine, a plurality of feed members, and flexible feeding elements cooperating respectively therewith, of guiding means for said flexible elements including a swing arm carrying a guide sheave and swingable into a plurality of positions on the machine, said sheave in one position adapted to be engaged by one flexible element and when in another position by said other flexible element.

8. In a mining machine, a plurality of feed members and flexible feeding elements cooperating respectively therewith, of guiding means for said flexible elements including a swing arm pivoted at the longitudinal vertical center of the machine and carrying a guide sheave with which either flexible element is adapted to engage, said arm being swingable to position said guide sheave at either side of the longitudinal vertical center of the machine.

9. In a mining machine having a forwardly projecting cutter bar, the combination with a feed member and a flexible feeding element cooperating therewith, of guiding means for said flexible element including a swing arm disposed adjacent said member and pivotally mounted on the machine at the rear side of said feed member at the rear end of the machine remote from said cutter bar and carrying a guide sheave, said swing arm being swingable vertically to locate said guide sheave in a plurality of different elevated positions wherein it is adapted to be engaged by said flexible element to guide the latter in a plurality of directions from said feed member.

10. In a mining machine, the combination with a plurality of feed members and flexible feeding elements cooperating respectively therewith, of guiding means for said flexible elements including guide sheaves about which the flexible elements are directly extended from said feed members and arranged at the opposite rear corners of the machine, said guide sheaves being adjustable into a plurality of positions wherein they are adapted to be engaged by said flexible elements to guide the latter as they extend tangentially in one or another of a plurality of directions from said feed members.

11. In a mining machine, the combination with a feed member disposed on a horizontal axis and a receding flexible feeding element cooperating therewith and extending laterally from the rear end of the machine, of guiding means for said flexible element including a swing arm pivoted on the machine to swing about an axis parallel with said feed member axis and carrying a guide sheave, said arm being swingable to position said sheave above and below a horizontal plane in which the feed member axis lies whereby the flexible element may be guided from either the top or bottom of the feed member.

12. In a mining machine, the combination with a plurality of feed members and flexible feeding elements cooperating respectively therewith, of guiding means for said flexible elements including a horizontal guide sheave with which either of said flexible elements is adapted to engage and adjustable into one position for engagement by one flexible element and in another position for engagement by said other flexible element.

13. In a mining machine, the combination with a feed member thereon and a cooperating receding flexible element extending laterally from the rear end of the machine, of guiding means for said flexible element including a swing arm pivotally mounted on a horizontal axis at the rear corner of the machine and carrying a guide sheave, said guide sheave being swingable into positions whereby it may be engaged by said flexible element when the latter is extended in a plurality of directions from said feed member.

14. In a mining machine, the combination with a feed member thereon and a cooperating receding flexible element extending laterally from the rear end of the machine, of guiding means for said flexible element including a swing arm pivotally mounted on a horizontal transversely extending axis at the rear corner of the machine and carrying a guide sheave, said guide sheave being swingable into positions whereby it may be engaged by said flexible element when the latter is extended in a plurality of directions from said feed member.

15. In a mining machine, the combination with a feed member thereon and a cooperating receding flexible element extending laterally from the rear end of the machine, of guiding means for said flexible element including a swing arm pivotally mounted on a horizontal axis at the rear corner of the machine at the rear side of the feed member and carrying a guide sheave, said guide sheave being swingable into positions whereby it may be engaged by said flexible element when the latter is extended in a plurality of directions from said feed member.

16. In a mining machine, the combination with a feed member thereon rotatable on a horizontal transversely extending axis and

- a cooperating receding flexible element extending laterally from the rear end of the machine, of guiding means for said flexible element including a swing arm disposed adjacent 5 said feed member and pivotally mounted on a horizontal axis at the rear corner of the machine at the rear of said feed member and carrying a guide sheave, said guide sheave being swingable into positions where-
10 by it may be engaged by said flexible element when the latter is extended in a plurality of directions from said feed member.
17. In a mining machine, the combination with a machine frame having feed members thereon and flexible feeding elements cooperating with said feed members, of guiding means for said flexible elements including a cylindrical member mounted transversely of the machine frame and having pivotally 15 mounted at its ends guide members for said flexible elements.
18. In a mining machine, the combination with a machine frame having feed members thereon and flexible feeding elements cooperating with said feed members, of guiding means for said flexible elements including a cylindrical member mounted transversely of the machine frame and having pivotally 20 mounted at its ends guide members for said flexible elements, and supplemental guide members non-rotatably mounted on said cylindrical member adjacent said pivotally mounted members.
19. In a mining machine, the combination with a machine frame having feed members thereon and flexible feeding elements cooperating with said feed members, of guiding means for said flexible elements including a cylindrical member mounted transversely of 25 the machine frame and having pivotally mounted at its ends guide members for said flexible elements, and supplemental guide members non-rotatably mounted on said cylindrical member adjacent said pivotally mounted members.
20. In a mining machine the combination with a feed member thereon and a cooperat- 30 ing flexible feeding element, of guiding means for said flexible element including a guide sheave, a support therefor, and a guide sheave pivotally mounted adjacent said support and swingable into different positions whereby the flexible element may be extended from the feed member tangentially in a plurality of directions, said support providing stops for limiting swinging movement of said pivotally mounted guide sheave.
21. In a mining machine, the combination with a machine frame having a feed member thereon and a flexible feeding element co- 35 operating with said feed member, of guiding means for said flexible element including a cylindrical member projecting laterally from said frame, a guide sheave support slidably mounted on said cylindrical member and having an abutment thereon engaging the frame to prevent rotative movement of said support about said cylindrical member, and a second guide sheave support pivotally mounted on said cylindrical member adjacent said first guide sheave support, said first guide sheave support providing means for limiting swinging movement of said pivoted guide sheave support.
22. In a mining machine, the combination with a feed member and a cooperating flexible element, of guiding means for said flexible element including a swing arm disposed adjacent said feed member and carrying a guide sheave rotatable about an axis perpendicular to the arm pivot axis, said arm being swingable to locate said sheave adjacent said feed member whereby said sheave may be engaged by said flexible element when the latter is extended in a plurality of directions from said feed member.
23. In a mining machine, the combination with a feed member and a flexible feeding element cooperating therewith, of guiding means for said flexible element including a swing arm pivotally mounted on the machine at the rear side of said feed member and carrying a guide sheave rotatable about an axis perpendicular to the arm pivot axis, said swing arm being swingable to locate said guide sheave in a plurality of positions wherein it may be engaged by said flexible element to guide the latter in a plurality of directions from said feed member.
24. In a mining machine, the combination with a feed member disposed on a horizontal axis and a flexible feeding element cooperat- 45 ing therewith, of guiding means for said flexible element including a swing arm pivoted on the machine to swing about an axis parallel with said feed member axis and carrying a guide sheave rotatable about an axis perpendicular to the arm pivot axis, said arm being swingable to position said sheave above and below a horizontal plane in which the feed member axis lies whereby the flexible element may be guided from either the top or bottom of the feed member.
25. In a mining machine, the combination with a feed member thereon and a cooperat- 50 ing flexible element, of guiding means for said flexible element including a swing arm pivotally mounted on a horizontal axis at the rear corner of the machine and carrying a guide sheave rotatable about an axis at right angles to the arm pivot axis, said guide sheave being swingable into positions whereby it may be engaged by said flexible element when the latter is extended in a plurality of directions from said feed member.
26. In a mining machine, the combination with a feed member thereon and a cooperat- 55

ing flexible element; of guiding means for said flexible element including a swing arm pivotally mounted on a horizontal transversely extending axis at the rear corner of the machine and carrying a guide sheave rotatable about an axis at right angles to the arm pivot axis, said guide sheave being swingable into positions whereby it may be engaged by said flexible element when the latter is extended in a plurality of directions from said feed member.

27. In a mining machine, the combination with a feed member thereon and a cooperating flexible element, of guiding means for said flexible element including a swing arm pivotally mounted on a horizontal axis at the rear corner of the machine at the rear side of the feed member and carrying a guide sheave rotatable about an axis at right angles to the arm pivot axis, said guide sheave being swingable into positions whereby it may be engaged by said flexible element when the latter is extended in a plurality of directions from said feed member.

28. In a mining machine, the combination with a feed member and a cooperating flexible feeding element, of guiding means for said flexible element including a swing arm pivotally mounted at the rear of said feeding member at the rear end of the machine and carrying a guide sheave rotatable about an axis at right angles to the arm pivot axis, said arm being swingable to locate said sheave in different elevated positions whereby it may be engaged by said flexible element when the latter is extended in a plurality of directions from said feed member.

In testimony whereof I affix my signature.

MORRIS P. HOLMES.
